(57) **CLAIM**

The ornamental design for the brush for cleaning hook and loop type fasteners, as shown.

DESCRIPTION

FIG. 1 is a top, rear isometric view showing the brush for cleaning hook and loop type fasteners according to my new design, the brush being shown in the closed position;

FIG. 2 is a bottom, rear isometric view thereof in the closed position;

FIG. 3 is a view similar to FIG. 1, the brush being shown in a partly open position;

FIG. 4 is a view similar to FIG. 2, the brush being shown in a partly open position;

FIG. 5 is a front elevation thereof;

FIG. 6 is a rear elevation thereof;

FIG. 7 is a side elevation thereof, the opposite side being a mirror image;

FIG. 8 is a top plan view thereof; and,

FIG. 9 is a bottom plan view thereof.
